(57) **CLAIM**

The ornamental design for an automobile vacuum pump canister as shown and described.

DESCRIPTION

FIG. 1 is a perspective view of my automobile vacuum pump canister;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front side view thereof;

FIG. 7 is a rear side view thereof; and,

FIG. 8 is another perspective view of my automobile vacuum pump canister.

The broken lines shown in the drawings illustrate portions of my automobile vacuum pump canister that form no part of the claimed design.
